US00D943518S

(12) **United States Design Patent** (10) Patent No.: **US D943,518 S**
Kihl et al. (45) Date of Patent: **** Feb. 15, 2022**

(54) **CHARGER FOR VEHICLES DRIVEN ELECTRICALLY**

(71) Applicant: **LG ELECTRONICS INC.**, Seoul (KR)

(72) Inventors: **Hewon Kihl**, Seoul (KR); **Sechang Park**, Seoul (KR); **Sangwon Yoon**, Seoul (KR); **Yongho Lee**, Seoul (KR); **Kyeongchul Cho**, Seoul (KR)

(73) Assignee: **LG ELECTRONICS INC.**, Seoul (KR)

(**) Term: **15 Years**

(21) Appl. No.: **35/509,076**

(22) Filed: **Oct. 16, 2019**

(80) **Hague Agreement Data**

Int. Filing Date: **Oct. 16, 2019**

Int. Reg. No.: **DM/204882**

Int. Reg. Date: **Oct. 16, 2019**

Int. Reg. Pub. Date: **Apr. 17, 2020**

(30) **Foreign Application Priority Data**

Apr. 26, 2019 (KR) 30-2019-0019837

(51) **LOC (13) Cl.** **13-02**

(52) **U.S. Cl.**

USPC **D13/107**

(58) **Field of Classification Search**

USPC D13/108, 110, 107; D14/307

CPC .. G07F 17/0042; B60L 11/1825; B60L 53/31; B60L 53/18; B60L 3/04

See application file for complete search history.

(57) **CLAIM**

The ornamental design for a charger for vehicles driven electrically, as shown and described.

DESCRIPTION

1. Charger for vehicles driven electrically

1.1 : Perspective

1.2 : Front

1.3 : Back

1.4 : Left

1.5 : Right

1.6 : Top

1.7 : Bottom

In the Reproductions, the broken lines are for the purpose of showing portions of the charger for vehicles driven electrically that form no part of the claimed design.

1 Claim, 7 Drawing Sheets
